STORAGE AND DISPENSER CABINET FOR BUTTER PATS

Robert G. Fraser, 2700 W. Farrell St.,
Park Ridge, Ill. 60068

Filed Jan. 19, 1966, Ser. No. 679

Term of patent 14 years

(Cl. D52—2)

FIGURE 1 is a perspective view of a storage and dispenser cabinet for butter pats showing my new design;

I claim:

The ornamental design for a storage and dispenser cabinet for butter pats, as shown.
